CLAIM

The ornamental design for the LED light fixture, as shown and described.

DESCRIPTION

FIG. 1 is a bottom perspective view of the LED light fixture showing my new design;

FIG. 2 is a bottom plan view thereof;

FIG. 3 is a top plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines depict portions of the LED light fixture in which the design is embodied and form no part of the claimed design.
